United States Patent Office

Des. 230,2

Patented Feb. 5, 19

230,238

PICTURE FRAME

Alfred Coda, 48 Wyandemere Drive,
Woodcliff Lake, N.J. 07675

Filed May 24, 1971, Ser. No. 143,705

Term of patent 14 years

Int. Cl. D6—07

U.S. Cl. D6—241

FIG. 1

FIG. 2

FIG. 3

FIG. 4

FIG. 5

FIG. 6

FIG. 1 is a perspective of a picture frame showing my new design;

FIG. 2 is a cross-sectional view taken along line 2-2 of FIG. 1;

FIG. 3 is a cross-sectional view taken along line 3-3 of FIG. 1;

FIG. 4 is a perspective view of an alternate form of the picture frame of FIG. 1;

FIG. 5 is a cross-sectional view thereof, taken along line 5-5 of FIG. 4; and

FIG. 6 is a cross-sectional view taken along line 6-6 of FIG. 4.

I claim:

The ornamental design for a picture frame, substantially as shown and described.
